HANDLE FOR COOKING UTENSILS
AND THE LIKE

James L. Hvale, Chicago, Ill., assignor to Eko Products Company, Chicago, Ill., a corporation of Illinois

Application January 14, 1949, Serial No. 234

Term of patent 14 years

(Cl. D44—29)

To all whom it may concern:

Be it known that I, James L. Hvale, a citizen of the United States, residing at Chicago, county of Cook, State of Illinois, have invented a new, original, and ornamental Design for a Handle for Cooking Utensils and the like, of which the following is a specification, reference being had to the accompanying drawing, forming part thereof.

Fig. 1 is a side elevation of a handle for cooking utensils and the like, showing my new design.

Fig. 2 is a top plan view thereof.

Fig. 3 is an end elevation thereof as viewed from the left hand side of Fig. 1.

Fig. 4 is a similar view as the same would appear when viewed from the right hand side of Fig. 1.

Fig. 5 is a vertical sectional view taken on line 5—5 of Fig. 1.

I claim:

The ornamental design for a handle for cooking utensils and the like, as shown.

JAMES L. HVALE.
